UNITED STATES PATENT OFFICE

169,235

CUP OR SIMILAR ARTICLE

Anton R. Backus, Santa Barbara, Calif.

Application June 12, 1950, Serial No. 10,474

Term of patent 14 years

(Cl. D44—9)

To all whom it may concern:

Be it known that I, Anton R. Backus, a citizen of the United States, residing at Santa Barbara, State of California, have invented a new, original, and ornamental Design for a Cup or Similar Article, of which the following is a specification, reference being had to the accompanying drawings, forming a part hereof, and in which:

Fig. 1 is a perspective view of a cup or similar article, showing my new design; and

Fig. 2 is a top plan view thereof.

I claim:

The ornamental design for a cup or similar article, as shown.

ANTON R. BACKUS.
